UNITED STATES PATENT OFFICE.

JOHN J. MEYERS, OF CINCINNATI, OHIO, ASSIGNEE TO J. A. FAY & EGAN COMPANY, OF CINCINNATI, OHIO, A CORPORATION OF WEST VIRGINIA.

BAND SAWING-MACHINE.

1,302,949.

Specification of Letters Patent.

Patented May 6, 1919.

Application filed October 11, 1917. Serial No. 195,950.

To all whom it may concern:

Be it known that I, JOHN J. MEYERS, a citizen of the United States, residing at Cincinnati, in the county of Hamilton and State 5 of Ohio, have invented certain new and useful Improvements in Band Sawing-Machines, of which the following is a specification.

It is the object of my invention to provide new and improved means in a band sawing machine, whereby the band-saw blade and the wheels about which the same moves, are combinedly tilted, so that the cutting stretch of the band-saw blade is caused to intersect the supporting surface for the work being sawed at any desired angle within quite a wide range at both sides of the vertical plane of said intersecting point; further, to provide improved means whereby the band-saw wheels are combinedly supported upon a supplemental frame which has arc-guide movement on a main frame in a circular path, which has the point of intersection between the cutting stretch of the band-saw blade and the supporting surface for the work being sawed, as its center, and so arranged that said cutting stretch is adjusted at angles to the vertical and to said supporting surface at both sides of the vertical; further, to provide improved means for accomplishing the adjustments of the supplemental frame; and, further, to provide improved arrangements of means mounted on and moving with the supplemental frame, forming a self-contained structure, for maintaining the driving relation for the band-saw blade from a source of power, throughout the range of adjustments of the cutting path of the band-saw blade to both sides of the vertical.

The invention will be further readily understood from the following description and claims, and from the drawings, in which latter:

45 Figure 1 is a front elevation of my improved device.

Fig. 2 is a rear elevation of the same.

Fig. 3 is a plan view of the same.

50 Fig. 4 is a vertical section, taken in the plane of the line 4—4 of Fig. 7, showing the rack and pinion connection for adjusting the supplemental frame.

Fig. 5 is a vertical section of my improved device, taken on the line 5—5 of Fig. 1.

Fig. 6 is a cross-sectional detail of the 55 same, taken on the line 6—6 of Fig. 1.

Fig. 7 is an enlarged plan section taken on the line 7—7 of Fig. 1.

Fig. 8 is a rear side elevation of the lower portion of the machine, showing the lower 60 band-saw wheel at the extreme right position of the present exemplification of my invention, looking toward the rear of the machine, in full lines, and at the extreme left position in dotted lines, to illustrate the self-contained character of the driving means and the freedom of the drive-belt for the lower band-saw wheel from interference in all positions of adjustment of the lower 65 band-saw wheel, and having the lower arc 70 retaining-piece for the outer guide removed for exposing the lower mounting for the supplemental frame.

Fig. 9 is an enlarged front elevation of one of the lower anti-friction mountings for the 75 supplemental frame.

Fig. 10 is an axial section of the same, taken on the line 10—10 of Fig. 9.

Fig. 11 is an axial section of the mounting for the shaft of the bell-crank lever of 80 the idler roller, taken on the line 11—11 of Fig. 3.

Fig. 12 is a cross-section of the same, taken on the line 12—12 of Fig. 3.

Fig. 13 is a cross-sectional detail of the 85 mounting for the lower saw-wheel arbor, taken on the line 13—13 of Fig. 6; and,

Fig. 14 is a cross-sectional detail of the same, taken in the plane of the line 14—14 90 of Fig. 13.

The main frame of the machine is indicated at 21. It comprises an arc casting, provided with an opening 22 at one side thereof, and having a foot-piece 23 at its lower portion adjacent to the opening. A 95 column 24 extends upwardly and has a laterally extending portion 25 which is rigidly connected with the laterally bulging portion of the main frame at 26, preferably by having mating faces respectively on the laterally extending portion of the column and on the main frame, the parts being connected by bolts 27. A recess 28 is thus formed between the column 24 and the main frame for a purpose hereinafter described.

100 The foot-piece and the column are provided with supporting faces 29, the downwardly bulging portion of the main frame

preferably extending below the horizontal planes of the supporting faces. These supporting faces represent the plane of the floor upon which the machine is set, the surface of the floor being represented by the dotted line 30. The arrangement is preferably such that the lower portion of the main frame and portions of the lower band-saw wheel and the driving means for the latter, are received in an opening in the floor, below the level of the floor, whereby the machine may be made of large size and the supporting surface 32 for the work being sawed may be brought sufficiently low with relation to the floor, so that an operator or the operators standing on the floor may conveniently manipulate the work and the machine. It also provides means whereby the driving means for the lower band-saw wheel and adjusting means for the supplemental frame may be made self-contained with the supplemental frame.

A work-supporting table 35 is supported from the main frame by means of webs 36 connecting the main frame with the table. The table may have friction reducing rollers 37 at its respective ends, and be provided with friction reducing short rollers 38 suitably supported within the same, adjacent to the path of the saw-blade, for aiding in feeding movement of the material at the point where it is subjected to the downward pressure of the cutting teeth of the saw-blade. The rollers have axles which are dropped into suitable slot-bearings of the table, so that the rollers are readily removable. The table is provided with a saw-slot 39 into which the saw-blade is received, and through the inner end of which the cutting stretch of the band-saw blade moves.

The band-saw blade is exemplified at 41, and is arranged to be received about an upper saw-wheel 42 and a lower saw-wheel 43. The upper saw-wheel is fixed to a saw-arbor 44 journaled in a bearing 45, supported on a block 46, the block being adjustable up and down in a guide 47. Suitable means may be provided for tilting and straining the upper saw-arbor, not more particularly shown because well-known.

A supplemental frame of arc form is formed of companion arc-slides 51, 52, which are adjustable along the lines of their arcs in both directions in arc-guides 53, 54, on the main frame. (See Figs. 1, 2, 3, 4, 5, 6 and 7.) The guides are formed by providing the main frame at each side thereof with a rabbet 56, the rabbet being of arc-form, and having an outer arc-guide wall 57 for the arc-slides. An arc retaining-piece 58 is received over the outer arc tongue 59 of each of the arc-slides and secured to the main frame by bolts 60. An inner arc retaining-piece 61 is received over an inner arc tongue 62 of each of said arc-slides, and

is secured to the main frame by means of bolts 63.

The forward arc-slide has a bracket 65 secured thereto, as by bolts 66, the bracket supporting the guide 47 for the bearing-block of the upper band-saw wheel. (See Figs. 1, 3 and 5.)

There is preferably a greater angular distance between the ends 67 of the forward arc-slide than between the ends 68 of the rear arc-slide. (Compare Figs. 1 and 2.) The guides for the forward arc-slide preferably extend throughout the extent of the arc of the main frame, while the rear arc-guides are preferably of less extent.

The lower band-saw wheel is fixed to a lower saw-arbor 71, which is journaled in bearings 72, adjustable in a bearing yoke 73, (see Figs. 6, 13 and 14), which is provided with extensions 74, 75, respectively secured, as by bolts 76, 77, to the respective arc-slides 51, 52. The yoke preferably extends integrally across the arc portion of the main frame, for forming a bearing-saddle, one of said extensions being preferably integral with said saddle and the other of said extensions being fixed to said saddle, as by bolts 78.

The bearings 72 are suitably adjustable in the bearing-saddle, as by providing the saddle with recesses 79, through which the lower saw-arbor is received, and with slots 80, forming guides for end-stubs 81 of the bearings. Plates 82 extend across said slots and are secured to the saddle by bolts 83. Adjusting bolts 84 are adjustable in threaded apertures in the plates, and impinge the bearing-stubs, for adjusting the bearings laterally and vertically, jam-nuts 85 fixing the bolts in adjusted positions. A bolt 86 is threaded through the bearing-saddle and impinges the upper face of each of the end-stubs 81 for adjusting the limit of upward movement of the bearing, a jam-nut 87 fixing the bolt in adjusted position.

An upper roller guide 91 for the saw-blade is rotatably supported on a rod 92, adjustable up and down in a bearing-piece 93, of a stand 94, fixed to the supplemental frame, as by bolts 95, and movable therewith. (See Figs. 1, 2, and 3.) A counter-weight 96 is connected with the rod 92 by means of a flexible connection 97 received over a pulley 98, rotatably supported in the upper end of the stand. The stand also supports a band-saw guard 99.

A lower roller guide 101 is provided for the band-saw blade, and is rotatably supported on a bracket 102, fixed to the forward slide of the supplemental frame, as by bolts 103. The roller guides and the stand and bracket move with the supplemental frame in the adjustments of the latter.

A saw-blade guard 105 is provided for 130

the rear or upwardly idle traveling stretch of the band-saw blade, and is provided with lugs 106 secured, as by bolts 107, to a bracket 108, fixed, as by bolts 109, to the front arc-slide of the supplemental frame.

The means for adjusting the supplemental frame in its arc-guides, are exemplified as comprising an arc-rack 111 on the inner face of the arc-slide 51. A bevel-gear

112 meshes with the rack through an opening 110 in the side of the main frame. (See Figs. 4, 6 and 7). The bevel-gear 112 is on a shaft 113, journaled in bearings 114 of the main frame and a bearing 115 in the column.

15 A worm-wheel 116 is fixed to this shaft. A worm 117 meshes with the worm-wheel, and is fixed on a shaft 118 journaled in bearings 119 in a bracket 120 extending from the column. A spur-gear 121 is fixed to the shaft 118. (See also Figs. 1, 2 and 3). A pinion 122 meshes with the spur-gear and is fixed to a shaft 123 journaled in bearings 124, on a gear-cover 125, fixed to the bracket 120 by bolts 126.

25 A hand-wheel 127 is on the shaft 123 for rotating the gear 112 manually, for manual adjustment of the supplemental frame arc-wise on the main frame, so as to position the cutting path of the saw-blade either in 30 a vertical position, or in a position at an angle to the vertical at both sides of the vertical, throughout a wide range of adjustment. The point in the cutting stretch of the saw-blade which intersects the 35 plane of the supporting surface of the table, instanced at 128, remains the same with relation to said supporting surface throughout said arc adjustments, so that the line of feed of the material may always 40 remain the same, with the assurance that the divergence of the cutting path of the saw-blade from said line of feed will be adjusted from the point of said line of feed at the supporting surface of the material.

45 The adjustments provided are especially useful in sawing ship timbers, which are large timbers, employed in the construction of vessels or water craft, and provides a quick, accurate and easy means for accomplishing the adjustments with speed, so that 50 great output by the machine is effected.

When adjusting the supplemental frame, therefore, the band-saw wheels, with the band-saw blade thereabout, the roller guides 55 above and below the table for the cutting stretch of the saw-blade, the supports for the roller guides, and the rear saw-guard, as well as the idler pulleys for controlling the path of the belt about the driving pulley 60 for the lower band-saw wheel, all move together in the adjustment of the supplemental frame. (See Figs. 1, 2 and 8).

The arbor of the lower band-saw wheel is provided with suitable driving means, exemplified as a pulley 131 fixed thereto. (See

Figs. 1, 2, 3, 5, 6, 7 and 8). A power transmitting pulley 132 is fixed to a drive-shaft 133 journaled in bearings 134 extending from the foot of the column 24. Suitable means are provided for driving the shaft 70 133. Such driving means may be either tight and loose pulleys on said shaft or a gear driven by an electric motor, or other well-known means.

A pulley 135 is on a shaft 136 journaled 75 in bearings 137 of a fork 138, formed on a hanger, pivoted on a stud-shaft 139 fixed in a bearing 140 of the foot-piece 23. The stud-shaft is centrally positioned in one end of the bearing 140, the other end of the bearing having its bore enlarged, as shown at 141, set-bolts 142 adjustable in the bearing impinging the shaft for adjusting its direction in order to properly track the belt received over the pulley 135. (See Figs. 11 85 and 12).

The bearing-saddle of the yoke 73 is provided with a bracket 144 having forks 145, 146, formed thereon, the forks having bearings 147, 148, thereon, for shafts 149, 150, 90 having pulleys 151, 152 thereon. The pulleys 151, 152 are belt directing pulleys. The pulleys 151, 152, as well as the bracket and its forks, move with the bearing-yoke 73 and the supplemental frame in the adjustment of the latter. 95

A belt or other flexible driving connection 154 is received about the power transmitting pulley 132, thence about the tightener pulley 135, thence about the directing idler pulley 131, 100 thence about the pulleys 152, 151, thence about the pulley 131 fixed to the lower saw-arbor, and back to the power transmitting pulley, the arrangement being such that the belt is caused to wrap about the pulley 131 on the lower 105 band-saw wheel arbor throughout a substantial part of its circumference and all other parts of the belt are kept away from said pulley, and the stretches of the belt to and from said pulley 131 are kept away 110 from contact with said pulley 131 or the belt thereabout, throughout all adjustments of the supplemental frame, whereby great power is transmitted by means of said pulley 131, and interference of said power 115 transmission is avoided, throughout the wide range of adjustments of the supplemental frame for positioning the path of the saw-blade throughout a wide range to both sides of the vertical plane of said path, 120 the adjustment being exemplified as an angular adjustment of ninety degrees, namely, forty-five degrees at each side of the normal vertical position of the cutting stretch of the band-saw blade. 125

The hanger 138 has an arm 155 extending therefrom, on which a weight 156 is arranged to be adjusted toward and from the pivot of said hanger for regulating the force applied to the tightener pulley 135, for 130

maintaining the belt in stretched relation about the pulleys and maintaining driving relation with the lower band-saw wheel pulley in all adjusted positions of the supplemental frame.

When the supplemental frame is adjusted for angular position of the upper portion of the cutting stretch of the band-saw blade about the table toward the opening in the 10 main frame, the lower band saw arbor and its saddle are received in the recess 28 formed between the main frame and the column 24. The parts are so arranged that even with extreme adjustment of the character 15 stated, great space is provided at the opening 22 for lateral insertion and removal of the timbers being cut.

The arm 155 is bent so as to place the weight outside the vertical path of the movements of the pulleys on the supplemental frame, when the supplemental frame is adjusted so as to adjust the angle of the cutting stretch of the band-saw blade. (See Fig. 3). An extreme adjustment of these 25 parts toward the right, looking toward the rear of the machine, is exemplified in full lines in Fig. 8, and an extreme adjustment of these parts to the left, is exemplified in dotted lines in this figure.

30 It will be noted that in all these adjustments the belt makes contact with a substantial part of the circumference of the pulley 131, and that the running parts of the belt are free from contact with each 35 other, so that there is no interference in the running of the belt, and further, that the idler pulleys 151, 152, placed in their relation to the pulley 131, prevent the stretches of the belt passing to and from said pulleys from interfering with the other 40 portions of the belts and other pulleys.

The construction and arrangement of the parts also provides means whereby the driving means for the lower band-saw wheel and 45 the means to be presently described for adjusting the supplemental frame on the main frame, are self-contained with and move as an entity with the supplemental frame in the adjustments of the latter.

50 Power means are provided for adjusting the supplemental frame, exemplified as comprising a pinion 158, fixed to a shaft 159, the inner end of which is journaled in a bearing 160 in the column, and the outer 55 end of which is journaled in a bearing 161, at the outer end of a bracket 162 extending from the column. (See Figs. 1, 2, 3, 5 and 7). Loose pulleys 163, 164 rotate loosely about said shaft, and a tight pulley

60 165 is fixed to said shaft between said loosely rotating loose pulleys. A drum-pulley 166 is fixed to the drive-shaft 133. A straight belt 167 is arranged to be received about said drum-pulley and either the loose 65 pulley 163 or the tight pulley 165. A

twisted belt 168 is received about said drum-pulley and either the loose pulley 164 or the tight pulley 165. When said tight pulley 165 is rotated by the straight belt, rotation of the pinion 158 is effected in one direction. When the twisted belt is received about said tight pulley, the said pinion is rotated in the opposite direction.

70 Means are provided for shifting the belts laterally from the operator's position at the machine, the operator's position being exemplified at A, or said belts may be laterally shifted automatically by the supplemental frame, for instance, when the supplemental frame has been moved in its arc, either while 80 feeding the material or between feeding movements of material, so as to have placed the cutting stretch of the band-saw blade at a predetermined angle with relation to the supporting surface of the material, either 85 to the right or left of the normal vertical plane of said cutting stretch.

85 Exemplifying this arrangement, I provide a rod 171 fixed in a bearing 172 in the column and a bearing 173 projecting 90 bracketwise from the bracket 162. The rod is non-rotatable, as for instance by being a square rod in square bearings. A hub 174 is slidable on the rod and is non-rotatable thereon, as by having a bore which fits the 95 square rod, and has belt-shifting fingers 175 projecting therefrom partway about the tight and loose pulleys about the shaft 159, and into the paths of the straight and twisted belts thereabout, for shifting said 100 belts respectively from either loose pulley about the tight pulley, or vice versa, or for placing said belts in idle relation about both loose pulleys.

105 A lever 176 is pivoted at 177 to a lug 178 extending from the column. The lever has articulation with the axially movable hub 174, as by means of a bolt 179 threaded into said hub and received through a slot 180 in said lever.

110 An axially shiftable rod 181 is movable in bearings 182 on the table, and at its forward end has a handle 183 thereon for shifting the same. A fork 184 is fixed to said rod, the tines of the fork being received about the 115 end of the lever 176, and being articulated therewith, as by a bolt 185 threaded in said fork and received through a slot 186 in said lever. By these means the adjustment of the supplemental frame along its arc in 120 either direction may be controlled for adjusting the angle of the cutting stretch of the saw-blade with relation to the plane of the supporting surface of the material.

125 Automatic means are provided for effecting cessation of adjusting movement of the supplemental frame, exemplified as accomplished by providing said lever with an arm 187, with which a link 188 is articulated at 189, the link being articulated at 190 to an 130

arm 196 of a bell-crank lever 191. (See Figs. 2, 3, 5, and 7). The bell-crank lever is pivoted by a bearing 192 about a shoulder-bolt 193 threaded into a plate 197 secured to 5 the frame. The other arm 198 of the bell-crank lever is provided with a slot 194 received about an arc-rod 195, shown as concentric with the arc-guides for the supplemental frame and as fixed to move with said. 10 supplemental frame. Thus the standard 47 for the adjusting block of the arbor of the upper saw-wheel is provided with a bracket 201, having a bearing through which the arc-rod extends. Jam-nuts 202, received about 15 the threaded end of said arc-rod at the respective sides of said bearing, secure said arc-rod to said bearing. The other end of the arc-rod is fixed to the bearing-saddle for the lower saw-arbor, as by being received 20 through an aperture in a lug 203 thereon, jam-nuts 204 being received at the respective sides of said lug for fixing the arc-rod in place.

The arc-rod is provided with adjustable 25 stops 205, 206, respectively above and below the laterally extending arm of the bell-crank lever, these stops being adjustable on the arc-rod, as by being fixed in adjustable positions thereon by set-bolts, so that when an 30 arc-movement of the supplemental frame, representing a predetermined angular position of the cutting path of the band-saw blade, has been completed, one of the adjustable stops will strike the said arm of the 35 bell-crank lever for shifting the belt-shifters to shift the belts into inoperative position, that is, shifting both belts upon the loose pulleys.

Permanent stops 209, 210, are also provided on said arc-rod, being fixed to said arc-rod in suitable manner, so as to prevent 40 adjustment or arc-movement of the supplemental frame beyond a predetermined angle of position of the cutting stretch of the 45 band-saw blade with relation to the supporting surface of the material.

In order to determine the angular position 50 of the cutting stretch of the band-saw blade, the main frame is provided with an arc-gage 211, with the marks of which a finger 212 secured to the supplemental frame is adapted 55 to register. (See Fig. 1).

I provide means whereby ease of adjustment of the supplemental frame is obtained 60 by relieving the pressure of the weight of the supplemental frame on the main frame, for accomplishing which I provide roller-bearings 215, 216, between the respective arc-slides 51, 52, and the main frame, the roller-bearings being at the respective sides of the 65 main frame in staggered relation to each other. (See Figs. 8, 9 and 10). The roller-bearings may consist of an inner cylinder 218, supported on a shoulder-bolt 219 screwed 70 into the main frame, there being a race of

rollers 220 about said inner cylinder, and an outer cylinder 221 about said race of rollers, the peripheral edges of the arc-slides bearing on the outer cylinders, so as to relieve the friction due to the weight of the supplemental frame on the main frame, and enabling the supplemental frame with the parts and operating devices thereon to be adjusted arcwise with ease, by the manual control means or the power control means. 75 These roller-bearings are located preferably only about the lower portion of the supplemental frame and are received in recesses 222 in the main frame, and covered by the guides 58. 80

Having thus fully described my invention, what I claim as new and desire to secure by Letters Patent, is:

1. In a band sawing machine, the combination of a main frame, a supplemental frame, a material-supporting member, an upper band-saw wheel and a lower band-saw wheel on said supplemental frame arranged for receiving a band-saw blade thereabout having a cutting stretch passing downwardly into said material-supporting member, and separated guiding means between said main frame and said supplemental frame, said guiding means comprising arc-guides on the outer opposite sides of said main frame, said supplemental frame comprising separated companion arc-slides coacting with said arc-guides, and connecting means extending crosswise of said main frame connecting said separated companion arc-slides in a rigid supplemental frame structure. 95

2. In a band sawing machine, the combination of a main frame, a supplemental frame, a material-supporting member, an upper band-saw wheel and a lower band-saw wheel on said supplemental frame arranged for receiving a band-saw blade thereabout having a cutting stretch passing downwardly into said material-supporting member, separated guiding means between said main frame and said supplemental frame, said guiding means comprising separated arc-guides on the outer opposite sides of said main frame, said supplemental frame comprising separated companion arc-slides coacting with said arc-guides, and connecting means extending crosswise of said main frame connecting said separated companion arc-slides in a rigid supplemental frame structure. 100

3. In a band sawing machine, the combination of a main frame, a supplemental frame, an upper band-saw wheel and a lower band-saw wheel on said supplemental frame 105

110

115

120

125

130

arranged for receiving a band-saw blade thereabout having a cutting stretch passing downwardly, and means for adjusting the angle of said cutting stretch to adjust the 5 upper portion thereof to both sides of the vertical comprising separated arc-guides on the outer opposite sides of said main frame, said supplemental frame comprising separated companion arc-slides distanced from 10 each other and coacting with said arc-guides, said respective arc-slides having a plurality of separated arc-guiding faces coacting with said respective arc-guides, said arc-guiding faces located in separated concentric paths 15 at different distances from the axis of said supplemental frame, and connecting means extending crosswise of said main frame connecting said separated companion arc-slides in a rigid supplemental frame structure, a 20 rack on the inner face of one of said arc-slides between the separated arc-guiding faces thereon, and a pinion in said main frame meshing with said rack.

4. In a band sawing machine, the combination of a main frame, a supplemental frame, a material-supporting member, an upper band-saw wheel and a lower band-saw wheel on said supplemental frame arranged for receiving a band-saw blade thereabout 25 having a cutting stretch passing downwardly into said material-supporting member, guiding means between said main frame and said supplemental frame, said guiding means comprising separated arc-guides on 30 the sides of said main frame, said supplemental frame comprising separated companion arc-slides coacting with said arc-guides, and connecting means extending crosswise of said main frame connecting said companion arc-slides in a rigid supplemental frame structure, an arbor for said lower band-saw wheel, and a pulley on said arbor, said pulley and lower band-saw wheel being at the respective ends of said arbor with 35 40 said connecting member and said arc-guides and arc-slides located between the same.

5. In a band sawing machine, the combination of a main frame comprising a substantially C-shaped member having separated substantially C-shaped side walls, a supplemental frame, a material-supporting member, an upper band-saw wheel and a lower band-saw wheel on said supplemental frame arranged for receiving a band-saw 50 blade thereabout having a cutting stretch passing downwardly into said material-supporting member, arc-guiding means between said main frame and said supplemental frame comprising separated arc-guides on 55 said separated substantially C-shaped side walls of said main frame, said supplemental frame comprising companion spaced-apart arc-slides coacting with said arc-guides, and a connecting yoke rigid with said arc-slides 60 65 forming a rigid supplemental frame struc-

ture, and an arbor for the lower band-saw wheel, said yoke comprising bearings for said arbor, the outer ends of which bearings are separated a greater distance than the distance between said arc-guides. 70

6. In a band sawing machine, the combination of a main frame, a supplemental frame, a material-supporting member, an upper band-saw wheel and a lower band-saw wheel on said supplemental frame arranged for receiving a band-saw blade thereabout having a cutting stretch passing downwardly into said material-supporting member, guiding means between said main frame and said supplemental frame arranged on the arc of a circle having the point of intersection of said cutting stretch and the plane of the material-supporting surface of said material-supporting member as its center, said guiding means arranged for adjusting said supplemental frame whereby to adjust said cutting stretch to adjust the upper portion thereof throughout angular distances at both sides of the vertical, an arbor for the lower band-saw wheel 80 journaled in said supplemental frame, a pulley thereon, a driving pulley and a directing pulley at the respective sides of said arbor and distanced therefrom, a plurality of idler pulleys about said arbor-pulley between said driving pulley and said directing pulley, said idler pulleys journaled on said supplemental frame and moving therewith, and an endless belt received about said pulleys, said belt forming a loop in which 90 said arbor-pulley is located and a reverse loop extending from said last-named loop in which said plurality of idler pulleys are located and constructed and arranged whereby one of the stretches of said last-named loop makes contact with all of said idler pulleys when said upper portion of said cutting stretch is adjusted to one side of the vertical, and whereby said last-named stretch makes contact with only a portion of 100 said plurality of idler pulleys when said upper portion of said cutting stretch is adjusted to the other side of the vertical. 110

7. In a band sawing machine, the combination of a main frame, a supplemental frame, a material-supporting member, an upper band-saw wheel and a lower band-saw wheel on said supplemental frame arranged for receiving a band-saw blade thereabout having a cutting stretch passing downwardly through said material-supporting member, guiding means between said main frame and said supplemental frame arranged on the arc of a circle having the point of intersection of said cutting stretch 115 and the plane of the material-supporting surface of said material-supporting member as its center, said guiding means arranged for adjusting said supplemental frame whereby to adjust said cutting stretch to ad- 120 125 130

just the upper portion thereof throughout angular distances at both sides of the vertical, an arbor for the lower band-saw wheel journaled in said supplemental frame, a 5 pulley thereon, a driving pulley and a directing pulley at the respective sides of said arbor and distanced therefrom, an idler pulley at each side of the vertical plane in which said arbor is located when said arbor 10 is in normal location, said idler pulleys journaled on said supplemental frame, the angular relations between said pulleys adjusted by adjustments of said supplemental frame, an endless belt received about said 15 pulleys, and constructed and arranged whereby to form driving connection by said belt between said driving pulley and said pulley on said arbor under freedom of reversely moving portions of said belt from 20 each other throughout the adjustments of said supplemental frame, and means connecting with one of said pulleys for stretching said belt.

8. In a band sawing machine, the combination of a main frame, a supplemental frame, a material-supporting member, an upper band-saw wheel and a lower band-saw wheel on said supplemental frame arranged for receiving a band-saw blade thereabout 25 having a cutting stretch passing downwardly through said material-supporting member, guiding means between said main frame and said supplemental frame arranged for adjusting said supplemental frame whereby to adjust said cutting stretch to adjust the upper portion thereof throughout angular distances at both sides of the vertical, an arbor for said lower band-saw wheel journaled on said supplemental frame 30 at the lower portion of said supplemental frame, a pulley thereon, a driving pulley and a directing pulley at the respective sides of said last-named pulley and distanced therefrom, a right line between the lower 35 points of the belt-supporting surfaces of said pulleys being below and distanced from said first-named pulley, and idler pulleys journaled on said supplemental frame above said first-named pulley between the vertical 40 plane in which the axis of rotation of said arbor is located when in normal position and said driving pulley and directing pulley respectively, and whereby a right line between the axes of said idler pulleys when extended intersects said first-named right line at opposite sides of said vertical plane when 45 said upper portion of said cutting stretch is adjusted to opposite sides of said first-named vertical, and arranged whereby a belt 50 received about said pulleys encompasses a substantial portion of said first-named pulley throughout the adjustments of said supplemental frame.

9. In a band sawing machine, the combination of a main frame comprising a sub-

stantially C-shaped portion and a column connected with the rear part of said C-shaped portion for forming an upwardly extending recess between said column and the lower rear curved part of said C-shaped 70 portion, said C-shaped portion provided with arc guiding means extending downwardly to substantial distance at one side of said recess, a supplemental frame comprising arc guiding means coacting with said first-named guiding means, an upper band-saw wheel and arbor on said supplemental frame, a lower saw-wheel arbor on said supplemental frame extending across said C-shaped portion, a band-saw wheel thereon, 75 said band-saw wheels arranged for receiving a band-saw blade thereabout having a cutting stretch passing downwardly, and means for adjusting said supplemental frame on said main frame for angular position of said cutting stretch to adjust the upper portion thereof to both sides of the vertical, whereby said lower saw-wheel arbor is received in said recess with said downwardly extending portion of said guiding 80 means extending downwardly past said lower saw-arbor during adjustments to one side of the vertical.

10. In a band sawing machine, the combination of a main frame comprising a substantially C-shaped portion, a floor-stand adjacent to the opening of said C-shaped portion, and a column extending upwardly and having connection with the rear curved part of said C-shaped portion forming a 95 space between said column and said C-shaped portion, said floor-stand and column having lower surfaces arranged for support on a floor, said C-shaped portion extending below the plane of said supporting surfaces, 100 a supplemental frame having arc-guide movement on said C-shaped portion, an upper saw-wheel arbor and a lower saw-wheel arbor journaled on said supplemental frame, said lower saw-wheel arbor extending across 105 said C-shaped portion, and a band-saw wheel on each of said arbors arranged for receiving a band-saw blade thereabout having a downwardly moving cutting stretch, and arranged for angular adjustments of 110 said cutting stretch to both sides of the vertical, whereby when said cutting stretch is adjusted to one side of the vertical said lower saw-wheel arbor is received along the downwardly projecting curved part of said 115 C-shaped portion toward said floor-stand and when said cutting stretch is adjusted to the opposite side of the vertical said lower saw-wheel arbor is received in said space between said column and said C-shaped portion.

11. In a band sawing machine of the character described, the combination of a main frame, a supplemental frame, a material-supporting member, an upper saw-wheel ar-

bor, a lower saw-wheel arbor, band-saw wheels thereon arranged for receiving a band-saw blade thereabout having a cutting stretch passing downwardly into said material-supporting member, guiding means between said main frame and said supplemental frame arranged on the arc of a circle having the point of intersection of said cutting stretch and the plane of the material-supporting surface of said material-supporting member as a center, said guiding means comprising inner and outer concentric guiding faces having radii of different lengths, a pulley on said lower saw-arbor, a driving pulley and a directing pulley at the respective sides of and spaced from said lower saw-arbor, a plurality of idler pulleys on said supplemental frame whose axes of rotation are located respectively adjacent to said inner and outer concentric guiding faces, arranged to permit adjustment of said supplemental frame and said saw-arbors with the saw-blade thereabout about said center during maintenance of relation of the axes of rotation of said idler pulleys to said concentric guiding faces, and the right lines between the axes of said idler pulleys at their respective limits of adjustment intersecting each other when extended.

12. In a band sawing machine, the combination of a main frame comprising a substantially C-shaped portion and a column connected with the rear part of said substantially C-shaped portion for forming a recess between said column and the lower curved part of said substantially C-shaped portion, said C-shaped portion provided with separated arc-guides on its opposite sides, a supplemental frame comprising separated companion arc-slides coaxing with said arc-guides, and connecting means extending crosswise of said substantially C-shaped portion connecting said separated companion arc-slides in a rigid supplemental frame structure with said arc-slides extending above said connecting means and having a recess therebetween, an upper band saw-wheel and a lower band saw-wheel on said supplemental frame arranged for receiving a band saw-blade thereabout, saw-arbors journaled on said supplemental frame for supporting said saw-wheels, a material-supporting member, the guiding faces of said arc-guides and arc-slides arranged on the arc of a circle having the point of intersection of the cutting stretch of said band saw-blade and the plane of the material-supporting surface of said material-supporting member as a center, and means to permit adjustment of said supplemental frame on said substantially C-shaped portion for angular positions of said cutting stretch to both sides of the vertical, where-

by said lower saw-wheel arbor is received in said first-named recess and said second-named recess is located proximate to the connection of said column with said substantially C-shaped portion, and with said upwardly extending portions of said arc-slides at the respective sides of said connection. 65 70

13. In a band sawing machine of the character described, the combination of a main frame comprising a substantially C-shaped portion and a column, said column having rigid connection with the median part of said portion for forming a recess between them, a supplemental frame comprising separated arc-guides coaxing with said portion at the respective sides of the latter, said arc-guides having a connecting member between their lower ends to form a recess between their upper ends, an upper saw-wheel arbor and a lower saw-wheel arbor journaled on said supplemental frame, and means to permit adjustment of said supplemental frame on said portion for locating said lower saw-wheel arbor and said connecting member in said first-named recess and said upper ends proximate to and at the respective sides of 80 85 90 said rigid connection.

14. In a band sawing machine of the character described, the combination of a main frame, a supplemental frame, a material-supporting member, an upper band-saw wheel and a lower band-saw wheel on said supplemental frame arranged for receiving a band-saw blade thereabout having a cutting stretch passing downwardly into said material-supporting member, arc guiding means between said main frame and said supplemental frame arranged on the arc of a circle having the point of intersection of said cutting stretch and the plane of the material-supporting surface of said material-supporting member as a center, said guiding means arranged for adjusting said supplemental frame for adjusting said cutting stretch throughout angular distances at both sides of the vertical, power means connecting with said supplemental frame for effecting said adjustments, shifting means for said power means, an arc-rod substantially concentric with said arc guiding means, adjustable stops adjustable along said arc-rod, and bell-crank means arranged for actuation of said stops for shifting said shifting means. 95 100 105 110 115

In testimony whereof, I have hereunto signed my name in the presence of two subscribing witnesses. 120

JOHN J. MEYERS.
